FIG. 1

FIG. 2

FIG. 3

FIG. 4

FIG. 5

FIG. 1 is a perspective view of our new and ornamental design for a ceiling runner from the bottom;

FIG. 2 is a top view of the ceiling runner of FIG. 1;

FIG. 3 is a bottom view of the ceiling runner of FIG. 1;

FIG. 4 is a side view of the ceiling runner of FIG. 1; and

FIG. 5 is a sectional view of the ceiling runner of FIG. 4.

The ceiling runner is shown broken away to indicate indeterminate length.

The dominant feature of our design resides in the high extent of the web and the flared opening of the bottom of the runner.

We claim:

The ornamental design for a ceiling runner, substantially as shown and described.
